UNITED STATES PATENT OFFICE

BURTON A. RUSSELL, OF WHITE PLAINS, NEW YORK, ASSIGNOR OF ONE-HALF TO
WALTER T. LAMOREAUX, OF WHITE PLAINS, NEW YORK

SOCKET WRENCH

Application filed May 5, 1927. Serial No. 188,913.

This invention relates to improvements in wrenches of the type commonly referred to as speed wrenches and particularly to a combination brace wrench with removable 5 sockets.

The present day brace wrenches with removable sockets have been partially satisfactory but have several serious difficulties such as one end only is adapted to receive a 10 detachable socket, the handle being on the other end and the socket receiving section is often very small and insufficient to withstand the tremendous torque generated in removing a rusted nut. Further, the cost 15 of making such a wrench, carefully fitting a handle and machining down the socket receiving end is extremely high, in view of the limited use of the usual brace wrench and, in certain uses, such as removing the demountable wheels of the disc or wire type from automobiles, a multiplicity of nut sizes are found, some of which are often so far indented 20 beyond the wheel hub, that it is practically impossible to reach them with the usual form of 25 turret or other socket wrenches.

It is, therefore, the principal object of this invention to produce a multiple ended, socket wrench in which the ends of the sockets extend sufficiently far beyond the brace part 30 as to unobstructedly reach the retaining means on demountable wheels.

It is another object of this invention to produce a more satisfactory, less expensive and more rugged brace wrench than has been 35 heretofore produced.

It is a further object of this invention to provide a wrench, each end of which is adapted to receive double ended sockets, one 40 of the sockets acting as a handle when the other is in use as a wrench thereby permitting efficient use of both ends of the wrench.

It is still another object of the invention to produce a wrench in which the socket receiving ends of the brace part are of several 45 different sizes so that a multiplicity of combinations of sockets may be resiliently attached to the brace.

It is still another object of this invention to produce a combination brace and socket wrench in which the double ended sockets are

resiliently held on each end of the brace member.

It is a still further object of this invention to produce a multiple ended socket for a multiple ended brace wrench in which the 55 ends or nut receiving portions of the double ended sockets are spaced sufficiently far apart to act as hand grips and to reach greatly indented wheel retaining nuts.

Further objects and advantages will appear as the following description illustrating one form of embodiment to which the invention is adaptable, proceeds and, in which,

Fig. 1 is a plan view of the assembled wrench.

Fig. 2 is a plan view, partially in section of the main or brace member with parts of the handle grip being in section.

Fig. 3 is a longitudinal sectional view of 70 one of the typical sockets.

Fig. 4 is a vertical cross sectional view on the line 4-4 of Fig. 2.

Fig. 5 is a vertical cross sectional view similar to Fig. 4 but on the line 5-5 of Fig. 2.

Fig. 6 is a cross sectional view of one of 75 the sockets on the line 6-6 of Fig. 3, and

Fig. 7 is an elevational view of a slightly modified form of the resilient socket receiving end of the brace.

The brace 10 shown in Figs. 1 and 2 is bent 80 from a bar which is preferably round spring steel to provide an intermediate portion 10^a over which a suitable sleeve 11 is placed to permit a rotatable hand grip and angular side portions 10^b together with end portions 85 12 and 14 which are in line with each other and parallel to the intermediate handle portion 10^a. On the end 12, a socket 16 is adapted to be resiliently secured and a similar socket 18 will fit over and be retained on the end 14. 90

It will thus be noted that a complete wrench comprises a brace 10 and two suitably secured sockets 16 and 18 on the ends thereof, the 95 sockets being in line with each other and either one of which may be the second handle grip for the wrench while the other end is in use.

In Fig. 2, the detailed construction of the handle grip 11 is shown in which the sleeve 100 is freely rotatable on the brace portion 10^a

and is prevented from undue endwise movement by the side or bent portions 10^b of the brace. Adjacent the end 12 of the wrench brace the socket receiving element is formed 5 into two hardened polygonal sections 12^a and 12^b, each of a different size corresponding with the form of a standard nut on which the wrench is to be used. For example, if it is desired to use the wrench on a general 10 class of hexagonal nuts or bolts, the sections 12^a and 12^b as well as the corresponding sections 14^a and 14^b will be hexagonal in shape. The sizes of the various sections will be determined by the usual size of nuts or 15 bolt heads to be encountered in use. For certain classes of work, such as that on an automobile, nuts and bolts of a similar size are very prevalent and for these various sizes each section would be of a corresponding 20 size. It is obvious that the smaller size must be on the outside or extreme end in order that the smaller socket will fit on.

A typical wrench for general automobile use might have the following sizes to fit hexagonal or SAE machine nuts and bolt head; 25 the portion 12^a—11/16", 12^b—5/8", 14^a—7/8", 14^b—3/4". This wrench is thus adapted for all sizes between 5/8" and 7/8" and is of a suitably heavy material throughout. 30 Many other combinations might be worked out, depending entirely on the use to which the wrench is to be put and one end might be adapted for square nuts or one side could be very large and the other very small. 35 It might be desirable to broach or otherwise form each socket end of two sizes, and with each brace end being of two sizes to fit the relatively smaller sizes in the socket end, it is obvious that a combination of eight sizes 40 is possible. The principle thing is that there is a multiplicity of combinations available on this simple double-ended brace wrench. Again, it might be desired to put on more than two socket receiving sections. It would 45 be very simple to so determine the respective sizes so that any reasonable number might be formed on each end.

To retain the sockets, the ends are provided with narrow flexible bands of spring 50 metal 20 as shown in Figs. 4 and 5 bowed at their centers and fastened on their ends rigidly to the collar 21 on the extreme end and movable under the collars 21^a on the other or inner end portion 12. A pin or solder is 55 sufficient to retain the outer end while an adequate slit or groove 22 in the collar 21^a will allow the other end to slide therein. The collar 21 is properly spaced and held by the extension piece 23 which also aids in guiding 60 the socket.

The typical socket 16 shown in Fig. 3 is formed with two hardened nut receiving ends 16^a and 16^b of the desired size joined 65 by a tubular section 16^c on which is a rotatable sleeve or ferrule 16^d to provide a freely

turning hand grip. Each of the ends of the socket is adapted to fit closely over the ends of the socket receiving portions 12^a or 12^b depending upon its size while the other end of the socket is available to be placed over a nut or bolt head to remove or tighten it, this socket member having freely rotatable handle grips 16^d or 18^d acting as a hand grip. The particular feature of the tubular spacing section 16^c is that it permits this double ended socket to be used as a solid handle grip for the brace wrench while the other end of the wrench is in engagement with a nut or bolt to be removed. It also is adapted to reach out of the way nuts or bolts. 70 75 80

In Fig. 6 the socket end 16^d is shown in end view. The particular shape either inside or out is immaterial and depends entirely upon the type and kind of nuts or bolts that the wrench will be used on. The showing is of 85 the typical 5/8" socket end. Of course each socket is in reality composed of two separate and distinct ends of different sizes, joined by a spacing section.

A slight modification of the means for 90 resiliently retaining the socket on the brace is shown in Fig. 7 in which the projecting end 30 of the brace beyond the nut or socket engaging portions 30^a and 30^b is provided with a 95 spacing member 31. Suitable holes 32 are drilled to receive ball engaging members 33 resiliently projected outward by springs 34 and then the recesses are suitably peened over on the outer edges at 35 to permanently retain the ball members. Such a construction 100 is equally as effective as the first form and merely illustrates a different form.

It will be understood that when the larger 105 end of a socket is attached to a brace, it will fit over the larger socket receiving portion and hence, will fit closer to the bend in the end adjacent the sides 10^b. In Fig. 1, both of the relatively smaller ends are shown cooperating with the socket receiving portions. When it is desired to have the larger nut receiving end of the socket exposed, it is merely necessary to draw the socket member off longitudinally to the brace end, reverse it and 110 reapply the smaller end of the socket to the socket receiving end on the brace. 115

Due to the fact that the socket receiving 120 section on the end of the brace is substantially the same size as the nut or bolt head which the open end is applied to, it is possible to exert a much greater force on the wrench without twisting the parts out of shape. In other words, besides the increased use of the wrench due to the multiple combinations on each end, a very weak link in the average wrench, namely, the reduced shank, has been 125 done away with. The sockets too are made with fewer operations and at a less cost because the ends which have to be exactly formed in any event, are connected together and no other machining is necessary. The 130

substitution of a useable socket for the handle, which has no other beneficial use is also a material economy.

Another adaptation of this wrench is that in connection with removing demountable wheels from an automobile when, as for example, a tire goes flat. In such cases, the retaining lugs on present day disc or wire wheels are out of reach of ordinary wrenches, and the obstacles of the various sizes, tight and rusted nuts, and the intervening spokes or hub parts are done away with by use of the herein described tool. At the same time, the other socket is acting as a substantial hand grip.

While I have shown certain particular details of construction to clearly illustrate my invention in accordance with the patent statutes, I am aware that other modifications may be made within the spirit and scope of the invention and I, therefore, desire protection on a broad interpretation of the invention within the limits of the appended claims.

I claim:

1. A socket wrench of the type described, comprising a brace shaped handle portion, the aligned ends of which comprise polygonal turning members of different sizes and adapted to selectively receive the polygonal sockets of double ended elongated tubular socket members, extensions beyond said polygonal turning members adapted to project into and support said tubular socket members adjacent their outer ends, and double ended tubular socket members having ends of different sizes adapted to be received upon each of said extensions, one end of each of said socket members engaging a turning member and the other end engaging the part to be turned, the portion of said socket member intermediate the sockets having rotatable sleeves thereon whereby it may selectively be used as a nut engaging member or as a non-slip handle.

2. A socket wrench of the type described, comprising a brace shaped handle portion, having polygonal turning members of different size adjacent the bends thereof, supporting members extending outwardly from said turning members and reversible double ended tubular socket members having end sockets of different size mounted on said extensions and which may be held and turned in the hand, the inner end of the socket members being adapted to selectively engage the turning members, while the outer end of the socket members are adapted to engage a nut, the supporting member supporting the socket member adjacent the nut engaging portion.

In testimony whereof I have affixed my signature to this specification.

BURTON A. RUSSELL.
